Curt Hermann Fleischer, Wethersfield, Conn.

Application September 16, 1935, Serial No. 40,809

5 Claims. (Cl. 46—28)

This invention relates to toys and has for an object to provide educational constructional material wherein series of units are shaped and cut to permit a child to interfit the same and build various miniature articles such as doll houses, furniture, castles, bridges and many other articles.

A further object is to provide educational constructional material which is simple in structural make up, which may be easily assembled for constructing miniature articles, and which will be light in weight, novel in form and inexpensive to manufacture.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a front elevation of a doll house built from certain of the units.

Figure 2 is an end elevation of the doll house.

Figure 3 is a front elevation of a chair built from certain of the units.

Figure 4 is a side elevation of the chair.

Figure 5 is a perspective view showing bars of different lengths constructed in accordance with the invention.

Figure 6 is a perspective view of a circular unit constructed in accordance with the invention.

Figure 7 is a perspective view showing semi-circular units of different sizes constructed in accordance with the invention.

Figure 8 is a perspective view of a plurality of bars differing from the bars shown in Figure 5 in that the ends are beveled and provided with notches normal to the bevel.

Figure 9 is a perspective view of a bar similar to the bars shown in Figure 8 except that the notches in the side edges are disposed at an acute angle to the median line of the bar.

Figure 10 is an end elevation showing stairways and sidings employing the bars shown in Figures 5 and 9.

Referring now to the drawings in which like characters of reference designate similar parts in the various views, 10 designates a plurality of bars, preferably rectangular and of light strong material. Each bar is provided in its longitudinal edges with notches 11 of such width

as to receive any other bar which may be inserted edgewise therein. Preferably the notches are rectangular and in depth may be one quarter the width of the bar so that when two bars are engaged where notches occur, each one extends half way across the other, so that a structure may be built up of bars showing no spaces between their adjoining edges as illustrated in Figures 1, 2, 3, and 5. The bars illustrated in Figure 5 may be used to construct siding, roofing, 10 walks, chairs and the like. The bars 10 have their end edges perpendicular to the side edges and provided with notches 12 at the centers extending parallel to the side edges and preferably rectangular and of the same depth as the notches 13 in the side edges.

Like the notches in the side edges, the notches in the end edges are adapted to snugly receive any other bar which may be inserted edgewise therein so that, as best shown in Figure 10, the 20 bars may be keyed together to form foundations, and as shown in Figures 3 and 4 to form keys for connecting various structural parts of miniature furniture.

For building gables for example and other articles where the units will extend in the form of a V relative to each other, as best shown in Figure 2, a plurality of bars 13 are provided, the bars varying in length and being similar in thickness to the bars 10. The bars 13 however are 30 provided with beveled ends 14 and notches 15 are formed therein normal to the bevel. Other notches 16 are formed in the longitudinal edges of the bars 13, these notches being similar in shape and in depth to the notches in the bars 10. 35 The beveled ends 14 permit of the bars 13 being butted end to end and slope or diverge from each other, and the notches 15 permit the bars 10 being received edgewise therein to key the bars 13 together as best shown in Figure 2.

In building stairways and other structures where horizontal and inclined elements make up the structure, bars 17 are provided, these bars being similar in outline and thickness to the bars 13 but differing from the latter by the provision 45 of notches 18 in one side edge formed at an oblique or acute angle to the median line of the bar. Thus when the bars 17 are set up with the beveled ends abutting bars 10 and being keyed thereto by other bars 10 received endwise in the 50 notches 19 in the beveled ends, as shown for example in Figure 10, to form a stairway for example, a plurality of the bars 10 may be engaged endwise in the oblique notches 18 and form the horizontal treads of the stairway.

Constructing miniature furniture such as an end table for example, a plurality of semi-circular units 20 are provided, each of these units being formed in the curved edge with radially formed notches 21 and in the straight edge being formed with notches 22 normal to the straight edge. The notches 21 and 22 are adapted to receive certain of the bars 10 placed edgewise therein either to form legs of an end table, for example, or to key the units 20 upon other articles as best shown in Figure 3.

To permit other articles of furniture, for example a center table being constructed, a plurality of circular units 23 are provided. Each unit 15 is provided in the circular edge with notches 24 extending radially and spaced substantially equidistant apart. These notches are adapted to receive certain of the bars 10 placed edgewise therein.

20 It will be apparent that the bars and units above described may be built up into a wide variety of forms and articles without the use of tools for changing or shaping the same and that the articles are fabricated with the fewest and 25 simplest possible connections.

From the above description it is thought that the construction and operation of the invention will be fully understood without further explanation.

30 What is claimed is:

1. Interlocking building material for miniature toys such as doll houses, furniture, castles, bridges, and so forth, comprising a plurality of bars provided in their longitudinal edges with oppositely disposed notches extending at a right angle to the median line of the bars, of such width as to receive any other bar which may be inserted edgewise therein, the bars having their end edges perpendicular to the side edges and provided with oppositely disposed notches coinciding with the median line of the bars and of the same depth as the notches in the side edges and adapted to receive any other bar which may be inserted edgewise therein so that the bars may be keyed together to form siding, roofing, walks, chairs and the like, in combination with similar bars provided with beveled ends and notches formed in the ends normal to the bevel, there being other notches formed in the longitudinal edges similar 45 in shape, in depth, and in angular inclination to the notches in the first named bars, the beveled ends permitting of the bars being butted end to end and slope or diverge from each other for building gables and other articles where the units 50 will extend in the form of a V relative to each other, the notches in the beveled ends of the second named bars permitting the first named bars being received edgewise therein to key all of the bars together.

60 2. Interlocking building material for miniature toys such as doll houses, furniture, castles, bridges, and so forth, comprising a plurality of bars provided in their longitudinal edges with oppositely disposed notches extending at a right angle to the median line of the bars, of such width as to receive any other bar which may be inserted edgewise therein, the bars having their end edges perpendicular to the side edges and provided with oppositely disposed notches coinciding with the median line of the bars and of the same depth as the notches in the side edges and adapted to receive any other bar which may be inserted edgewise therein so that the bars may be keyed together to form siding, roofing, walks, 65 chairs and the like, in combination with similar

bars provided with beveled ends and notches formed in the ends normal to the bevel, there being other notches formed in the longitudinal edges similar in shape, in depth, and in angular inclination to the notches in the first named bars, the beveled ends permitting of the bars being butted end to end and slope or diverge from each other for building gables and other articles where the units will extend in the form of a V relative to each other, the notches in the beveled ends of the second named bars permitting the first named bars being received edgewise therein to key all of the bars together, in combination with a plurality of circular units provided in the circular edge with notches extending radially and spaced substantially equidistant apart and adapted to receive certain of said bars placed edgewise therein to 10 form the horizontal treads of the stairway.

3. Interlocking building material for miniature toys such as doll houses, furniture, castles, bridges, and so forth, comprising a plurality of bars provided in their longitudinal edges with oppositely disposed notches extending at a right angle to the median line of the bars, of such width as to receive any other bar which may be inserted edgewise therein, the bars having their end edges perpendicular to the side edges and provided with oppositely disposed notches coinciding with the median line of the bars and of the same depth as the notches in the side edges and adapted to receive any other bar which may be inserted edgewise therein so that the bars may be keyed together to form siding, roofing, walks, chairs and the like, in combination with similar bars provided with beveled ends and notches formed in the ends normal to the bevel, there being other notches formed in the longitudinal edges similar in shape, in depth, and in angular inclination to the notches in the first named bars, the beveled ends permitting of the bars being butted end to end and slope or diverge from each other for building gables and other articles where the units will extend in the form of a V relative to each other, the notches in the beveled ends of the second named bars permitting the first named bars being received edgewise therein to key all of the bars together, in combination with a plurality of circular units provided in the circular edge with notches extending radially and spaced substantially equidistant apart and adapted to receive certain of said bars placed edgewise therein to 15 form the horizontal treads of the stairway.

4. Interlocking building blocks for miniature toys including a plurality of bars of rectangular cross section and of various lengths, certain of said bars each having beveled ends and oppositely disposed notches in their edges at equal distances from the ends of the bars and longer bars having such notches at intervals of equal length, said notches extending into the edges of the bars to a distance substantially one fourth 20 of the width of the bars whereby when bars are interlocked with each other by said notches they will overlap half way of each other and bars engaging opposed notches of another bar will have their adjacent edges in engagement 25

and whereby the bars may be variously interlocked with other bars and have their opposed notches cooperate with notches of adjacent bars in the various interlocked relationships, and said 5 beveled ends each having similar inwardly extending notches intermediate the edges of the bars perpendicular to the end edges for cooperation with notches in the edges of other bars.

5. Interlocking building blocks for miniature 10 toys including a plurality of bars of rectangular cross section and of various lengths, said bars each having oppositely disposed notches in their edges at equal distances from the ends of the bars and longer bars having such notches at intervals of equal lengths, said notches extending 15 into the edges of the bars to a distance substantially one fourth of the width of the bars where-

by when bars are interlocked with each other by said notches they will overlap half way of each other and bars engaging opposed notches of another bar will have their adjacent edges in engagement and whereby the bars may be variously interlocked with other bars and have their opposed notches cooperate with notches of adjacent bars in the various interlocked relationships, other rectangular bars having equally spaced inclined notches in one edge thereof for 10 engaging bars by cooperating with notches thereof, and the ends of said bars also having similar inwardly projecting notches perpendicular to the end edges for cooperating with notches in the edges of other bars. 15
